UNITED STATES PATENT OFFICE.

SIEGMUND LUBIN AND SOLOMON DRYFOOS, OF PHILADELPHIA,
PENNSYLVANIA.

DESIGN FOR A PRISM-PLATE.

SPECIFICATION forming part of Design No. 30,471, dated April 4, 1899.

Application filed February 21, 1899. Serial No. 706,418. Term of patent 7 years.

To all whom it may concern:

Be it known that we, SIEGMUND LUBIN and SOLOMON DRYFOOS, residing in the city of Philadelphia, State of Pennsylvania, have invented and produced a new and original Design for Prism-Plates, of which the following is a specification.

Figure 1 is a plan view of a prism-plate embodying our new design. Fig. 2 is a sectional view taken on the line A A of Fig. 1. Fig. 3 is an end elevation at right angles to the line A A.

As shown in the drawings, the leading or material feature of our design consists of a series of parallel cylindrical concavities 1,

disposed or arranged upon one side of the plate, as shown in Figs. 1 and 2, while the opposite side of the plate comprises a series of parallel prismatic ribs 2, as shown.

Having described our invention, what we claim as new, and desire to secure by Letters Patent, is—

The design for a prism-plate, as herein shown and described.

SIEGMUND LUBIN.
SOLOMON DRYFOOS.
